UNITED STATES PATENT OFFICE

ROBERT DAVID MAYO, OF TOLEDO, OHIO.

LIFE-BOAT.

No. 899,672.

Specification of Letters Patent.

Patented Sept. 29, 1908.

Application filed November 28, 1904. Serial No. 234,443.

To all whom it may concern:

Be it known that I, ROBERT DAVID MAYO, a citizen of the United States, residing at Toledo, Lucas county, Ohio, have invented 5 certain new and useful Improvements in Life-Boats, of which the following is a specification that will enable those skilled in the art to which the invention pertains to make and use the same, reference being had to the accompanying drawings, forming a part thereof.

This invention relates to the class of life boats in which is employed an outer cylindrical shell provided with an inner carriage 15 or cradle which is supported in the shell and is capable of independent rotary movement about the axis thereof.

The principal object of this invention is to construct the outer shell of sheet metal or 20 other suitable sheet material, in "knock-down" or detachable sections so that it may be constructed in parts that may be packed in small compass for transportation and thereafter readily assembled and connected 25 to form the boat.

A further object of this invention is to strengthen the sheet metal shell without the employment of other devices that would obstruct free passage through the boat from 30 end to end, or access to its entire inner surface.

A further object of this invention is to provide suitable means for the introduction and circulation of air through the boat, while 35 water shipped in at the air openings in the shell is caught and discharged through proper scupper pipes.

A further object of this invention is to provide an inner carriage or cradle that will be 40 supported by, but revolve independently of the shell upon annular rings built into the shell, and to provide said carriage with a central hollow rib or keel structure, and with side seat structures, both of which are divided by transverse partitions into compartments 45 adapted to contain supplies of food or water, or to receive and hold air tight tanks.

The further objects of this invention consist in such details of construction and assemblage of parts as shown in the drawings 50 and as will hereinafter be fully described and claimed.

The accompanying drawings show this invention in such general form and details of 55 construction as now appear most desirable, but changes, not requiring the exercise of in-

vention, might be made therein by a skilful mechanic without departing from the spirit of my invention, as set forth in the claims at the end of this specification.

Figure 1 is a longitudinal section through a life boat embodying the features of this invention. Fig. 2 is a transverse section of the same on the line 2, 2 of Fig. 1. Fig. 3 is a sectional view on enlarged scale of the details of one of the annular seam joints reinforced by the annular roller ring. Fig. 4 is a sectional view of the same on the line 4, 4 of Fig. 3. Fig. 5 is an enlarged longitudinal section on the line 5, 5 of Fig. 6 of one end of the outer shell etc. of the boat, preferably the rear end. Fig. 6 is a transverse section of the same on the line 6, 6 of Fig. 5. Fig. 7 is a view of a portion of the inner face of the shell showing the crossing of a longitudinal and an annular seam or joint in the shell. Fig. 8 is a perspective view, on reduced scale, of one of the sheet metal side-plate sections of the outer shell, detached. Fig. 9 is a similar view of the meeting point of four of such sections or side-plates and the meeting or intersecting point of the longitudinal and annular seams. Fig. 10 is a view in sectional elevation on enlarged scale, of the ends of one abutting pair of side plates. Fig. 11 is a detail view showing the joining of the sectional ribs of the shell to each other and to the longitudinal tee irons.

A life boat embodying this invention consists, mainly, of an outer cylindrical shell A, 90 with rounded or spherical head or end sections B, and an inner carriage or series of carriages C, supported from the outer shell in such manner as to be free to rotate independently about the axis thereof.

The principal object of my invention is to so construct the outer shell in "knock-down" sections that may be taken apart and closely packed for shipment and reassembled and connected at the point where used. To this 95 end I make the boat shell in several longitudinal sections or lengths; the two rounded ends B being preferably made in separate sections and the intermediate portion of the shell in one, or as many more sections as may be deemed desirable a standard size for such a boat would be about thirty feet in length, over all, and about six and one half feet in diameter, and such a boat would preferably have its central portion A made in two longitudinal sections.

In addition to dividing the shell into the

- longitudinal and end sections, just described, I also divide the circumference of each of these sections and ends into sub sections or plates D, Fig. 10, which run lengthwise of the shell 5 and around the rounded ends as will be easily understood. In each section these plates are united by means of outwardly turned side flanges d ; between which, in assembling, is located the web e of a tee iron bar 10 which runs from the bow to the stern of the shell, and has its foot or base e' lying inside of the shell. A U shaped wale strip e^2 embraces the projecting edges of the flanges and tee iron, and has flanged feet bases e^3 which 15 bear against the outer surfaces of the plates and are secured in position by rivets or bolts as desired. It is preferable to cover the outer surface of the shell plates with a covering a , of asbestos-wool and canvas, and when 20 this is used, the covering extends under the bases of the wale strips and serve as gasket packings to assist in making water-tight joints at these points, as shown in Figs. 9 and 10.
- 25 In practice I prefer to divide each part and end piece of the boat shell for a boat of the size mentioned, into say eight sections, so that there will be eight longitudinal seams E, such as just described, running the entire 30 length of the boat from bow to stern, but it must be understood that the tee irons e, e' are the only continuous members in such seams. These longitudinal seams E running the length of the shell, give it additional stiffness 35 and projecting, as they do, from the outer surface, they act as keels or fins, and check the rolling slip of the shell in the water thus making the boat a much steadier sailor.
- In addition to the side seams just described, 40 the several longitudinal sections of the shell are joined by inturned annular flanges f , formed on the ends of the several plate sections, see Figs. 8, 9 and 10. These flanges f , when the plates of two shell sections are 45 brought together, form a continuous annular rim F, of double thickness which is embraced by a U shaped annular ring f' , and all secured in place and held together by suitable rivets or bolts, as desired.
- 50 Where the flanges f meet at the longitudinal seams, each flange end is recessed or undercut as at f^2 to permit of the passage of the foot or base e' of the continuous tee irons of the longitudinal seams; and if the legs of the 55 U shaped ring f' extend far enough they too must be notched for these tee irons.
- The end sections B of the shell, are rounded as shown and provided with end openings b, b' , the opening b at the stern being large 60 enough to admit of the passage of a man while the bow opening b' is intended principally for a hawse opening and for ventilating purposes. In these end sections are secured inwardly projecting tubes G, G', provided at 65 their inner ends with inturned annular

flanges g , the openings through which are smaller in diameter than the adjacent portion of the tube. These tubes may be made conical, as shown at G, in Figs. 1, 5 and 6, or they may be plain cylindrical tubes as shown at G' 70 in Fig. 1, but in either event, the opening in the flange g must be smaller in diameter than the tube in order to check such water as may be driven into the outer open end of the tube, which, it is contemplated, will be left open at 75 all times except in extremely rough weather, when they may be stopped or closed by plugs or doors of any desired form. In these tubes G, G' are formed at or near their largest diameters, series of holes g' connected by radiating scupper pipes g^2 to corresponding holes g^3 80 through the shell. These scupper pipes serve to drain off water which may find its way into the tubes, and also to admit air for ventilating the vessel; the lowermost pipes at 85 any time acting as drains, while the others are open to the air.

The inner ends of the tubes G, G' are braced from the shell by radial rods g^4 , secured at one end to the pipes, and at their 90 other ends to the inturned annular joint-flange F of the shell, which affords a convenient means for attachment. This also aids to stiffen the entire shell structure at this point, the rods g^4 serving to brace the shell itself as 95 well as hold the tubes in position.

In order to further provide against the ingress of water through the end tubes into the living space in the shell catch basins H are provided and mounted upon the flanges g as 100 follows: On each flange is mounted a collar H' preferably made of two stamped sheet metal rings h with closely abutting ribs h' at their inner edges. Between these rings are anti-friction rollers h^2 carried by bearing pins 105 h^3 which pass through the rings and are provided with clamping nuts h^4 . These rollers run upon the inner edges of the flanges g and give free rotary motion to the collars. At the outer edge of each collar ring is an annular gasket or packing ring h^5 , of soft material adapted to make a water tight joint with the flange g at this point. This collar may be clamped tight to the flange and its independent rotation stopped by tightening the nuts 110 h^4 on the roller pins.

The basins H have flanged ribs h^6 which rest against the inner faces of the collars and afford means for detachably securing the basins to the collars; and they are also provided with means for connecting the basins to the carriages or cradles so that they shall rotate in unison therewith and always remain right side up, as will hereinafter be explained.

It will be observed that the lips h^7 of the basins stand through the collars so that any water from the basin will discharge outside of the flanges g and into the spaces drained by the scupper pipes.

The carriages or cradles C in which the passengers are carried in the vessel are located in the shell between the flanges g, g, of the end tubes, and these carriages are so mounted 5 in the shell that they maintain a position below the axis of the shell regardless of the rolling motion of the shell.

In order that the space for the carriages in the shell may be clear from end to end, and 10 unobstructed by bulkheads, open frames or other like supports the carriages C are supported by rings I mounted upon annular rings or flanges J, which are secured to the sides of the shell. These rings J are formed 15 with flanged feet j which bear against the shell sides, and with webs j' which bear against the inturned shell flanges F, and with flanged heads j², which overhang the feet, and form tracks for the anti-friction rollers k, 20 supported in carrier rings K. The carrier or cradle rings I have flanges i at their edges to give them strength and to form tracks, for the rollers k, which are opposed to tracks j² of the shell rings.

25 The carriages or cradles may be formed in any suitable manner, but in the drawings I have shown them as composed of sheet metal bodies c, semi-cylindrical in shape and reinforced at each end by channel iron bars or 30 yokes c', with straps or bands c² attached to the ends of the channel irons and passing over the tops of the rings I so that the weight and load of the carriage is carried by the tops rather than the bottoms of said rings. These 35 straps c² are preferably provided with turn-buckles c³, or devices of similar character to adjust their lengths and the heights of the carriage.

Instead of the sheet of metal which forms 40 the floor or body of the carriage, it may be composed of longitudinal slats or of any other well known construction.

45 Each carriage is formed with a hollow longitudinal keel or strengthening rib M, rigidly secured to the frame and preferably divided by transverse partitions m into compartments which may contain supplies of food and water or air-tight tanks.

Secured to the ends of the keel box are 50 angle iron braces m' which extend in under the ring I and give additional strength at this point.

55 At the sides of the carriage are formed seats N running lengthwise, which may also be divided by cross partitions into compartments to contain supplies or air tanks.

In addition to the main flanges or internal ribs F, the shell is strengthened annularly by intermediate ribs O, shaped as shown and 60 spaced at suitable intervals. These ribs are made in sections corresponding to the width of the longitudinal sections of the shell and where they meet at the longitudinal seams of the shell the meeting ends lap past and telescope as shown in Fig. 11 so that base flanges 65

of both ends may be secured to the tee iron e' by bolts or rivets. The carriage bottom is also strengthened by similar ribs P secured to its outer surface and preferably spaced intermediate the shell ribs O. In order that the 70 catch basins H, on the tube flanges g, may always retain a vertical position regardless of the rolling of the shell, a cross bar Q is arranged to be connected at its ends to the ring I of the carriage or cradle and to have a saddle q formed at its center and adapted to bear up the inner end of the basin; while a notch q' in the bar, receives a rib h⁸ on the basin so that the basin and the rotating collar H', on which it is mounted, are compelled 80 to follow the swing of the carriage rather than the roll of the shell.

At times it may be desirable to entirely close the opening through the collar and above the basin, and to this end a rod R detachably resting in suitable catches r, on the collar, has two doors or leaves s, s' hinge-mounted upon it and adapted to close the collar and basin openings respectively, as shown in Fig. 5.

90 It will be understood, of course, that the outer shell is provided with suitable hatches or man-holes, and with covers therefor, and also with dead lights and other such appurtenances as are common and so well known 95 in the art that it is not deemed necessary to illustrate them in this application.

Having thus described my invention what I claim as new and useful and desire to secure by Letters Patent is:

1. In a life boat, the combination of a cylindrical outer shell composed of sheet material and divided into separable lengths or sections with inturne annular flanges at the abutting ends of the sections and U shaped 105 annular rings which embrace each pair of flanges and means for securing the flanges and U shaped rings together to form water tight joints, substantially as described.

2. In a life boat, the combination of a cylindrical outer shell composed of sheet material and divided into separable longitudinal sections, with out-turned flanges at the abutting edges of the sections and U shaped wale strips embracing each pair of flanges, substantially as described.

3. In a life boat, the combination of a cylindrical outer shell composed of sheet material and divided into separable longitudinal sections with out-turned flanges at their abutting edges and U shaped wale strips embracing each pair of flanges and having flanged feet which bear against the shell at each side of the flanges, substantially as described.

4. In a life boat, the combination of a cylindrical outer shell composed of sheet material and divided into separable longitudinal sections with out-turned flanges at their abutting edges, tee iron bars having their bases inside the shell and their webs projecting out-

wardly and lying between the flanges of adjacent sheets, with means for securing the flanges and tee iron bars together, substantially as described.

5. In a life boat, the combination of a cylindrical outer shell composed of sheet material and divided into separable longitudinal sections with out-turned flanges at their abutting edges, tee iron bars having their bases inside the shell and their webs projecting outwardly and lying between the flanges of adjacent sheets, with U shaped wale strips embracing the flanges and intervening web of the tee iron and having flanged feet which bear upon the outer surface of the shell, substantially as described.

6. In a life boat, the combination of a cylindrical outer shell, composed of sheet material and divided into separable longitudinal and transverse sections, the sheets composing these sections being outwardly flanged at their edges for the longitudinal seams and inwardly flanged at their ends for the annular seams, substantially as described.

25. 7. In a life boat, the combination of a cylindrical outer shell composed of sheet material and divided into separable longitudinal and transverse sections, the sheets comprising these sections being outwardly flanged at 30 their edges for the longitudinal seams and inwardly flanged at their ends for the annular seams, and tee iron bars having their webs lying outwardly between the flanges of the longitudinal seams and their bases against the 35 inside of the shell, with notches cut into the ends of the inwardly turned annular flanges of the sheets for the bases of the tee irons, substantially as described.

8. In a life boat, the combination of a cylindrical outer shell composed of sheet material and divided into separable lengths or sections with inturned annular flanges at the abutting ends of the sections which form annular rings, annular bearing rings or tracks 45 supported thereby, with an internal cradle or carriage in the shell, rotatable independently of the shell and supported by said annular bearing rings or tracks, substantially as described.

50. 9. In a life boat, the combination of a cylindrical outer shell composed of sheet material and divided into separable lengths or sections with inturned annular flanges at the abutting ends of the sections and annular 55 rings secured to the flange joints, and an internal carriage adapted to be supported by said annular rings and rotatable independently of the shell, substantially as described.

10. In a life boat, the combination of a cylindrical outer shell composed of sheet material and strengthened by internal annular flanged ribs, a carriage in said shell adapted to rotate independently of the shell and annular bearing rings for supporting said carriage having flanged feet which bear on the

inner surface of the shell and vertical webs which bear against and are secured to the sides of the shell ribs and overhanging flanges or heads which form the supporting track for the carriage.

70. 11. In a life boat, the combination of a cylindrical outer shell having closed ends with a central aperture through each end, a tube extending inwardly from each end and larger in some portion of its diameter than the aperture in the end of the shell, an inturned apertured flange at the inner end of such tube, with an open frame work consisting of radial brace rods which support the inner end of the tube from the shell, substantially as described.

75. 12. In a life boat, the combination of a cylindrical outer shell having closed ends with a central aperture through each end, a tube extending inwardly from each end and having an apertured flange at its inner end, a rotatable collar mounted in the aperture of the flange and an inwardly projecting catch basin attached to said collar, substantially as described.

80. 13. In a life boat, the combination of a cylindrical outer shell having closed ends with a central aperture through each end, a tube extending inwardly from each end, a centrally apertured flange on the inner end of the tube, 90 a rotatable collar mounted in the aperture of the flange and a catch basin carried by said collar, with a carriage in the shell and independently rotatable about the axis thereof, and means whereby the basin and its collar 95 are connected to the carriage so as to rotate in unison therewith, substantially as described.

100. 14. In a life boat, the combination of a cylindrical outer shell having closed ends with a central aperture through each end, a tube extending inwardly from each end and a centrally apertured flange on the inner end of the tube, a rotatable collar mounted in the aperture of the flange, said collar comprising two 105 side plates with meeting flanges on their inner edges, anti-friction rolls between the side plates and bearing on the inner edge of the tube flange, pivot bolts for said rolls with clamping nuts on their ends, and gasket 110 packing rings on the adjacent faces of the side plates near their peripheries, substantially as and for the purpose described.

115. 15. In a life boat, the combination of a cylindrical outer shell having closed ends with a central aperture through each end, a tube extending inwardly from each end and a centrally apertured flange on the inner end of the tube, an open top basin supported in the opening of the flange and extending inwardly 120 therefrom, with hinged doors to close the opening in the flange above the basin, and to close the open top of the basin, substantially as described.

125. 16. In a life boat, the combination of a cy-

lindrical outer shell composed of sheet material and divided into separable longitudinal sections with out-turned flanges at their abutting edges and tee iron bars between adjacent flanges, shaped sectional ribs lying 5 annularly inside the shell and adapted to meet at the longitudinal joints, the meeting ends passing and telescoping at such joints so that the base flanges of both sections may 10 be secured to each other and to the base of

the tee iron in the same, substantially as described.

In testimony whereof, I have signed my name to this specification in the presence of two subscribing witnesses.

ROBERT DAVID MAYO.
